(57) **CLAIM**

We claim the ornamental design for a tool for a vacuum cleaner, as shown and described.

DESCRIPTION

FIG. 1 is a bottom perspective view of a tool for a vacuum cleaner showing our new design;

FIG. 2 is a top perspective view thereof;

FIG. 3 is a front view thereof;

FIG. 4 is a rear view thereof;

FIG. 5 is a side view thereof;

FIG. 6 is a side view of the opposite side of FIG. 5;

FIG. 7 is a top view thereof; and,

FIG. 8 is a bottom view thereof.

The dash-dot-dash lines represent boundary lines. The uniform dashes represent structure that forms no part of the claimed design.
